UNITED STATES PATENT OFFICE.

LOUIS FELD, OF PHILADELPHIA, PENNSYLVANIA.

GAS-HEATED IRON.

1,117,017.

Specification of Letters Patent. Patented Nov. 10, 1914.

Application filed October 31, 1913. Serial No. 798,463.

To all whom it may concern:

Be it known that I, LOUIS FELD, a citizen of the United States, residing in Philadelphia, Pennsylvania, have invented certain 5 Improvements in Gas-Heated Irons, of which the following is a specification.

My invention relates to sad irons heated by the flame of a gas burner, and consists of a number of details of construction designed to improve sad irons of this character.

One object of my invention is to provide means for circulating air through the handle-carrying bracket.

15 A further object is to provide an elongated retaining screw for holding the burner in place; such screw being provided with a non-heating head and operable from a point near the handle. And a still further object is to provide an improved form 20 of burner; one that will provide for a straight flame projecting well beyond said burner, and at the same time one that will permit of the ready introduction of a fresh 25 sheet of wire screen should occasion demand.

These and other features of my invention are more fully shown hereinafter, reference being had to the accompanying drawings, 30 in which:

Figure 1, is a sectional elevation of a gas heated sad iron having and containing the improvements forming the subject of my invention, and Fig. 2, is a perspective view 35 of the bracket-support for the handle of the same.

In the drawings, 1 represents the body of 40 the sad iron, which may be of any usual construction, and which may have a flame deflector 2 within the same, held in place by a screw 3. A handle 4 is provided, carried by a bracket 5, which may be secured to the body of the iron by a pair of screws 6. The bracket 5 supporting the handle, 45 being of metal and in direct contact with the iron, heats very rapidly, and for the purpose of ventilating the same to as great an extent as possible, I preferably form apertures in the end portions of the bracket, 50 as clearly shown at 7 and 8. The metal of the aperture 7 is entirely removed, while the metal of the rear aperture 8 may be pressed up to form a support 8^a, herein-after described.

55 10 represents a burner, which in general is of the usual construction, fitting the rear

of the sad iron. This burner has a flange 11 fitting a recess 12 in the lower portion of the iron, and it is arranged to be confined in place by a screw 13 engaging the upper portion of the burner. In this instance, said screw 13 passes through an aperture 14 in the bracket 8^a, before referred to, and through an aperture 15 in a rear portion or extension 1^a of the top 65 of the iron; such screw having a conical or beveled end 16 to engage the beveled wall 17 of the shell or casting forming the burner 10. The screw 13 is quite long, and is provided with a handle or knob 18 of 70 fiber or similar insulating material so as to be non-heating. As shown, it is disposed close to the handle of the sad iron so as to be readily operated by the user when it is desired to disconnect the burner 75 from the iron, without danger of burning the fingers.

The shell of the burner 10 forms a chamber 21, the outer wall of which is threaded at 22 to receive a cap sleeve 23 having a 80 flange 24 whereby a sheet of wire screen 25, through which the gas passes, may be held in proper place with respect to the burner. By preference, the inner diameter of the chamber 21 is less than the inner 85 diameter of the flange 24 engaging the edge of the screen.

I claim:

1. The combination of an iron having an aperture in the rear portion of the top of 90 the same, a handle bracket, a burner fitting the iron and having a beveled wall, and a screw carried by the handle bracket for holding said burner in place, said screw being elongated and being threaded into 95 the aperture of the iron for engagement with the beveled wall of the burner.

2. The combination of an iron having an apertured rear extension, a handle bracket having an apertured supporting portion, a 100 burner fitting the iron, and a screw for holding said burner in place, said screw being elongated and passing through the apertured bracket support and being threaded into the rear extension of the iron 105 for engagement with the burner.

3. The combination of an iron having an apertured rear extension, a handle bracket having an apertured supporting portion, a 110 burner fitting the iron and having an engaging portion, and a screw for holding said burner in place, said screw being elongated and being threaded into the rear extension of the iron for engagement with the burner.

gated and passing through the apertured bracket support and being threaded through the extension of the iron for contact with the engaging portion of the burner, said screw having a beveled end whereby the burner may be moved into and held in proper position.

4. The combination of an iron having an aperture in the rear portion of its top, a handle bracket, a handle carried thereby, a burner fitting the iron, and a screw carried by the handle bracket for holding said burner in place, said screw being elongated and threaded into the aperture of the iron for engagement with the burner and having its operating end adjacent the handle of the iron.

5. The combination of an iron having an aperture in the rear portion of its top, a handle bracket, a handle carried thereby, a burner fitting the iron, a screw carried by the handle bracket for holding said

burner in place, said screw being elongated and threaded into the aperture of the iron for engagement with the burner, and a non-heating manipulating element carried by said screw adjacent the handle of the iron.

6. The combination of an iron having a rear extension with a threaded aperture, a handle bracket having a guiding support, a burner fitting the iron and having a beveled wall on its upper side, and a screw for holding said burner in place, said screw being elongated and passing through the bracket support and through the rear extension of the iron for engagement with the beveled wall of the burner.

In testimony whereof, I have signed my name to this specification, in the presence of two subscribing witnesses.

LOUIS FELD.
